UNITED STATES PATENT OFFICE.

CLINTON L. BOPP, OF HAWKEYE, IOWA, ASSIGNOR OF ONE-FOURTH TO JOHN BEAL, OF WHITTIER, CALIFORNIA.

INDUCTION-COIL.

No. 844,240.

Specification of Letters Patent.

Patented Feb. 12, 1907.

Application filed October 21, 1905. Serial No. 283,818.

To all whom it may concern:

Be it known that I, CLINTON L. BOPP, a citizen of the United States, residing at Hawkeye, in the county of Fayette and State of Iowa, have invented certain new and useful Improvements in Induction-Coils; and I do hereby declare the following to be a full, clear, and exact description of the invention, such as will enable others skilled in the art to which it appertains to make and use the same.

This invention relates to improvements in induction-coils, and particularly to those kind that will produce a pulsating and alternating current at will.

The object in view is the production of means for producing comparatively high potential alternating currents from a comparatively low potential pulsating current.

A further object in view is the provision of means for producing at will either alternating or pulsating currents at comparatively high potential from pulsating currents of comparatively low potential.

With these and further objects in view this invention consists in the combination, with a soft-iron core surrounded by inner windings of comparatively large wire and the outer windings of comparatively fine wire, of two sets of electrical magnets for making and breaking the circuit in order to produce pulsating currents in the primary winding of the coil and alternating or pulsating currents of higher potential in the secondary winding.

This invention also consists in certain other novel constructions, combinations, and arrangement of parts, as will be hereinafter fully described and claimed.

In the drawing the figure represents a diagrammatic view of one embodiment of my invention.

It has been desirable in telephone test sets or for use in ringing signal-bells to have a device which could produce either an alternating or pulsating current. The induction-coil which forms the subject-matter of the present invention is designed to supply this need, as it will produce an alternating current for telephones or a pulsating current for polarized bells at the will of the operator by simply switching either line in or out, as may be desired.

In carrying out the features of the present invention I employ an induction-coil consisting of a soft-iron core 1, preferably of fine wire, a primary winding 2 of comparatively large wire, and a secondary winding 3 of comparatively fine wire wound on a suitable number of spools 4 and connected in series.

5 indicates a suitable box containing the induction-coil and having on one side thereof a vibrator 6 and a relay 6^a, that is used for producing the pulsation in the secondary winding when pulsating currents are needed. The vibrator consists of a pair of electromagnets 7 for attracting a suitable armature 8, with an adjustable weight 9 placed on the armature 8 for regulating the vibration of said armature. Adjusting-screws 10 and 11 are also employed to limit the vibration of the armature, as well as to form binding-posts for the electrical circuits. The armature is secured to a spring 12, which is rigidly fastened at 13 and has spring-vibrators 14 and 15 for making contact alternately with said screws 10 and 11.

Connected in series with the vibrator is a device that may be termed a "relay" for producing pulsating current in the secondary winding. This relay consists of a pair of electromagnets 16 and armature 17, held in place by a suitable spring 18 and an adjusting-screw 19. There is also a weight 20 placed on the outer end of the supporting-spring 18 for regulating the vibration of the armature 17. The normal position of the armature is such that the contact-points 21 and 22 are held out of contact, so that no current will flow through the relay unless the armature has been drawn down by an independent source of electricity. The magnets of the vibrator and relay are connected in series through wire 23, the vibrator 14, armature-spring 12, wires 24, 25, 26, 27, and 28, and thence through a closed-circuit battery 29. A current of electricity passing from battery 29 to a binding-post 30 through wire 23, vibrator 14, armature-spring 12, and thence through the electromagnets 7 and 16 and back to the battery through the binding-post 31 will attract the armatures 8 and 17 and permit the passage of a current of electricity through the primary winding, as will presently be described. When the armature

14 of the vibrator has been attracted by a current of electricity passing through the magnet 7, the vibrator 15 will contact with set-screw 11, closing the primary circuit. When 5 the primary circuit is thus closed, a current of electricity will flow from the battery 32 through binding-post 33, wire 34, set-screw 11, armature 8, armature-spring 12, wire 24, wire 34', and thence through the winding 2, 10 wire 35, and back to the battery 32 through wire 35 and the binding-post 36. In the primary winding is placed a condenser 37 to bridge across the contacts of vibrator 14 and set-screws 11.

15 When it is necessary to secure an alternating current, battery 29 is connected to binding-posts 30 and 31, which will cause the vibrator to make and break the circuit of the primary winding, thus causing a pulsating 20 current to flow from battery 32 through said primary winding. As the pulsations rise in the primary winding 2 the lines of force will pass upward and be cut by the secondary winding, causing an induced current of electricity to flow through wires 38 and 39, and as the current decreases in coil 2 the lines of force will gradually contract and again be cut by the secondary winding, which will cause an induced current to flow through 25 wires 38 and 39 in an opposite direction to the first induced current. As the pulsations continue in the primary winding this alternating current will continue to flow and with as rapid alternations as may be desired, as 30 the vibrator may be caused to vibrate either slowly or rapidly by the adjustment of the weight 9 on the spring of the armature 8. The wire 38 is connected to binding-post 40, through which the current passes, then 35 through a switch 40', when the same is closed, wire 50, any suitable device, as a bell 44, using alternating currents, thence through wire 45, switch 46, binding-post 47, wire 39, and back to the point of generation.

45 When it is desired to secure pulsating currents, the battery 29 is connected to the binding-posts 30 and 31 and the current from said battery passes through the same winding as when it is desired to secure alternating currents; but the pulsating current is received from binding-posts 40 and 41. As 50 the vibrator causes the primary circuit to send pulsations through the winding 2 the lines of force will be projected through the secondary winding, thus causing an induced current to flow through wires 39 and 42, switch 46 being open, contacts 21 and 22, armature 17, armature-spring 18, wire 43, binding-post 41, through wire 48, any suitable device using pulsating currents, as a bell 49, wire 50, switch 40', and back through binding-post 40 and wire 38 to the point of generation, thus completing the circuit.

When the pulsation in the primary wind-

ing decreases, the lines of force will contract, 65 but no current will flow from the secondary winding, as the magnets 16 have released the vibrator arm or armature 17, thus opening the circuit. By thus closing the circuit of the secondary winding at every other alternation a pulsating current of electricity of comparatively high potential is secured from a pulsating current of comparatively low potential.

Having thus fully described my invention, 75 what I claim as new, and desire to secure by Letters Patent, is—

1. The combination with an induction-coil having two separate generators of electricity, of a device for using a current of one 80 source of generation for actuating a vibrator and the current of the other source of generation for sending pulsating currents through the primary winding of said induction-coil.

2. An induction-coil comprising a core, a 85 primary winding and secondary winding, and means for securing alternating and pulsating currents at will from said secondary winding.

3. The combination with an induction-coil, of a vibrator for causing pulsation of an 90 electrical current to pass through the primary winding of said induction-coil, a second vibrator or relay for suppressing one of the alternations induced in the secondary winding.

4. An induction-coil comprising a primary and secondary winding, means for causing an electrical current to pass through the primary winding, a vibrator connected in series with the means for producing pulsation in the 100 primary winding for transmitting pulsating currents from the secondary winding.

5. An induction-coil comprising a core, a plurality of windings, and means for securing alternating and pulsating currents from one 105 of said windings.

6. The combination with an induction-coil of a vibrator, comprising an interrupting device, and means for permitting a pulsating current of electricity to pass through the 110 primary winding of said induction-coil, the said current being derived from an independent source to that of a current operating said vibrator.

7. The combination with an induction-coil, of a vibrator for causing pulsating currents to pass through the primary winding of said induction-coil, a second vibrator connected in series with the first vibrator for permitting only one of the induced currents 120 to flow from the secondary winding.

8. The combination with an induction-coil, of a vibrator for sending pulsating currents through the primary winding of said induction-coil, a second vibrator with means 125 for adjusting the vibration thereof in order to keep step with one of the alternations of the primary winding.

9. The combination with an induction-coil, of a vibrator, means for furnishing current to the said vibrator, and independent means for furnishing pulsating current to the primary winding of said induction-coil. 5
10. The combination with two sources of electrical current, of an induction-coil comprising a core, a plurality of windings, means for causing the current from one of said 10 sources to permit pulsating currents to flow from the other source of electrical energy.
11. An induction-coil comprising a primary and a secondary winding, means for causing a pulsating current to pass through said primary winding, and means for producing pulsating currents in said secondary winding. 15
12. An induction-coil comprising a primary winding, a secondary winding, means 20 for causing a pulsating electrical current to pass through said primary winding, and means for securing pulsating currents from said secondary winding of higher potential than the potential of the current passing 25 through said primary winding.
13. An induction-coil comprising a primary and secondary winding, means for causing electrical current to pass through said primary winding, and means for produc-
- ing pulsating and alternating currents from 30 said secondary winding.
14. An induction-coil comprising a primary winding, and a secondary winding, means for passing a current through said primary winding, means for receiving pulsating currents from said secondary winding and means for varying the pulsation of said current. 5
15. The combination with an induction-coil, of a vibrator comprising an interrupting device, means for permitting a current of electricity to pass through the primary winding of said induction-coil, and means for producing a pulsating current in the secondary winding. 40
16. The combination with an induction-coil, of a vibrator for permitting pulsating currents to pass through the primary winding of said induction-coil, a second vibrator, and adjustable means positioned on said second vibrator for regulating the vibration thereof. 45
- In testimony whereof I affix my signature in presence of two witnesses.
